(57) **CLAIM**

The ornamental design for a bracket set applied to a window treatment, as shown and described.

DESCRIPTION

FIG. 1 is a perspective view of a bracket set applied to a window treatment showing our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged partial view of the bracket of FIG. 1. The broken line showing of a bracket set is for the purpose of illustrating portions of the article and forms no part of the claimed design. The broken line showing of a window treatment is for the purpose of illustrating environmental structure and forms no part of the claimed design. In FIG. 8, the circular broken line identifies an enlargement.
